UNITED STATES PATENT OFFICE.

LAWRENCE McCALL, OF PERU, INDIANA.

SASH-FASTENER.

SPECIFICATION forming part of Letters Patent No. 250,562, dated December 6, 1881.

Application filed July 9, 1881. (Model.)

To all whom it may concern:

Be it known that I, LAWRENCE McCALL, a citizen of the United States, residing at Peru, in the county of Miami and State of Indiana, 5 have invented certain new and useful Improvements in Sash-Fasteners; and I do hereby declare that the following is a full, clear, and exact description of the same, reference being had to the annexed drawings, making a part of 10 this specification, and to the letters and figures of reference marked thereon.

Figure 1 of the drawings is a front elevation of a window frame and sash, partly in section, showing the application of my invention. Fig. 15 2 is a detail view of the spring-rod-fastening device, with a portion of the window-sash in dotted lines, showing the position of the fastening device with relation to the notches upon the sash. Fig. 3 is a perspective view of the 20 window-frame, with the molding connected thereto for concealing the fastening device; and Fig. 4 is a plan view of the same with the molding removed.

The present invention has relation to that 25 class of sash fasteners or locks composed of a spring-arm or other like device adapted to engage with notches or a serrated bar on the window-sash for holding it at any height or fastening the sash closed, as desired.

30 Previous to my invention the particular construction of these fastening devices rendered them very expensive as well as difficult in applying to the window-frame. Ordinarily these fasteners were provided with a knob, 35 button, or other device for operating them, which were disposed upon the outside of the window-frame in view. Therefore it was an easy matter for a person on the outside of the window to break one or more of the panes of 40 glass, reach his hand through, release the fastening device by pressing upon the knob or button, disengage it from the sash and raise the same, thereby affording no security against 45 thieves unless the well-known locking devices operated with a key are employed, which are not only expensive and complicated, as a general thing, but are at times impracticable.

The object of my invention is to provide a simple, cheap, and practical fastening device 50 that can be readily attached to the window-frame with comparatively slight alteration of the same, thereby enabling it to be sold in

sets in the market ready for immediate application to the window-frame, and when thus connected and the window-sash fastened the 55 sash cannot be opened by any one on the outside by breaking a pane of glass and reaching his hand through, as the manner of connecting it to the window-frame completely conceals it from view, requiring a suitable key to 60 operate it. These objects I attain by the construction substantially as shown in the drawings and hereinafter described.

In the accompanying drawings, A represents the window-frame, and B the sash, said frame 65 having connected thereto a suitable molding, a, which extends around its four sides. The sash B is provided upon one of its edges with inclined notches b and a notch, c, with which the fastening device engages when it is desired 70 to fasten the window closed, the inclined notches serving to hold the window-sash open at any height required.

The fastening device is of peculiar form, it being composed of a steel or other spring-wire, 75 C, of sufficient length to give it the required elasticity. The wire C is disposed within a recess, d, formed in the frame A, the lower end of the wire being bent at right angles, as shown at g, so that it may be driven in the frame A, 80 this being all that is necessary to securely fasten the wire to the frame. The opposite or upper end of the wire C is bent at a right angle, as shown at e, and again at right angles, as shown at f, Fig. 2. The wire forming the last- 85 mentioned angle is of sufficient length to form a wide and firm bearing for the face of the notches b, and consequently a complete lock for the sash.

An opening, h, is formed in the frame A at the upper end of the recess d, and at a right angle thereto, to receive the angle f of the wire and allow it to move horizontally in the opening to release it from the inclined notches b or notch c.

The moldings a i, which are ordinarily used 95 in window-frames, serve to completely conceal the fastening device from view.

To operate the fastening a suitable key is necessary, its shank being flat and inserted into the narrow opening h through the molding 100 i, and by pressing down or outward the angle f of the wire C the same will be disengaged from the notches in the sash.

As the fastening device is wholly concealed

by the moldings *a i*, should a person from the outside break the glass for the purpose of raising or opening the window the fastening device could not be operated without possession of the 5 key, thereby making the fastening a very secure one against parties from the outside.

The manner of bending the wire *C* is deemed of importance, it not only forming a complete fastening device, but one that is simple, easy 10 of attachment to the window-frame, and that can be manufactured at a trifling cost, there being no additional springs or other devices necessary to render it operative, or screws or other similar fastenings for securing it to the sash.

15 The entire fastening device, as will be seen, is composed simply of a piece of spring-wire bent in the form shown, and, as heretofore, there is no knob or button on the end of the fastening for operating it, nor is it composed of sheet 20 metal. This latter form, although common, is not considered practical, as the sheet metal is not as strong and durable as the wire, and besides there is increased expense in their manufacture, as well as making it, in most cases, 25 necessary to use screws to connect them to the window-sash, while my device is connected by the staple end *g*.

Having now fully described my invention,

what I claim as new, and desire to secure by Letters Patent, is—

1. The combination, with the window-sash *B*, having the notches *b c*, of the spring-wire *C*, having the staple end *g*, for attaching it to the window-frame, and at its opposite end bent, as shown and described, to form the two angles *e f*, said wire being disposed within the recesses *d h* of the frame and concealed from view by the moldings *a i*, the latter having an opening, *k*, through it for the reception of a suitable key for operating the fastening device, substantially as and for the purpose set forth. 30

2. As an improved article of manufacture, a sash-fastening device consisting of the spring-wire *C*, bent, as shown and described, to form the two angles *e f*, and at its opposite end bent 35 to form a staple, *g*, for attaching it to the window-frame, substantially as and for the purpose specified.

In testimony that I claim the above I have hereunto subscribed my name in the presence 40 of two witnesses.

LAWRENCE McCALL.
